UNITED STATES PATENT OFFICE.

FRED W. WOLF, OF HONOLULU, TERRITORY OF HAWAII, ASSIGNOR TO F. W. MACFARLANE, OF HONOLULU, TERRITORY OF HAWAII.

PINEAPPLE CORING AND SLICING MACHINE.

1,142,216.

Specification of Letters Patent.

Patented June 8, 1915.

Application filed October 12, 1914. Serial No. 866,330.

To all whom it may concern:

Be it known that I, FRED W. WOLF, a citizen of the United States, residing at Honolulu, island of Oahu, Territory of Hawaii, have invented a new and useful 5 Pineapple Coring and Slicing Machine, of which the following is a specification.

The object of my invention is to provide 10 a pineapple slicing and coring machine constructed to perform both operations successively in and automatically by my invention.

Among the objects of my invention is the 15 provision of novel slicing means, novel coring means and novel means for holding the pineapple during the coring and slicing operations.

It is my object to provide novel elements 20 in such a machine and to combine and arrange the various parts of the machine in a novel and improved way.

I attain these and other objects of my invention as hereinafter more fully disclosed, by the mechanism illustrated in the accompanying drawings, in which—

Figure 1 is a side elevation of my machine; Fig. 2 is a top plan of the machine; Fig. 3 is an end elevation of the body of the machine; Fig. 4 is an enlarged detailed 30 sectional view of the turret and slicing means; Fig. 5 is a vertical sectional view approximately on line 5—5 of Fig. 4, showing the cover plate of the lower knife brace removed; Fig. 6 is a detail sectional view 35 of the coring means, on line 6—6 of Fig. 4; Fig. 7 is a detail view of the hub of the turret; Fig. 8 is a detail view on line 8—8 of Fig. 2, showing in detail the Geneva movement; Fig. 9 is an enlarged detail of 40 the outer sleeve guard 48.

Like characters of reference refer to like parts throughout the several views.

Referring to the accompanying drawings, mounted on a suitable supporting frame I 45 provide a main driving shaft 2, operated by pulley 1 and clutch 3. Mounted on the main driving shaft 2 is a bevel gear 4 meshing with bevel gear 5 on an upright shaft 7, which is supported by bracket 6. Mounted on the upper end of the shaft 7 is a crank disk 8, to which is secured a pitman 9. The opposite end of the pitman 9 is connected to crosshead 10, the latter being slidable

on guide rods 11, which are supported by castings 12 on the frame. Crosshead 10 in 55 turn operates coring tube 40.

On main driving shaft 2 are keyed disks 13 and 14, between which is mounted a locking hub 15. Inserted in disks 13 and 14 is a pin 16 (see Figs. 2 and 8) which operates 60 the Geneva wheel 17, which is keyed on turret shaft 18.

Mounted on turret shaft 18 is the turret 19, which, as illustrated in Figs. 5 and 1, is composed of a series of novel hooked, star-pointed plates or disks 20, spaced apart one from the other by offset ribs 21. The series of disks 20 are held together by bolts 23 and hub members 22 which bolts 23 fasten together. A hub or spacing sleeve 70 24, mounted on shaft 18 operates to prevent hub members 22 from becoming too tight. The series of disks 20 revolve between two turret castings 25 which are mounted on the main framework of the machine. Spaced 75 diagonal braces 26 are provided, as illustrated in Figs. 3 and 4, between which is mounted the lower knife holder 28, to which is secured the lower end of the turret castings 25, as shown at 27 in Fig. 3. An upper 80 knife holder 29 is provided, mounted on a shoulder portion 30 of turret casting 25. Rotatably mounted on top of the turret castings as shown at 31 in Fig. 4 is a shaft 32 to which is attached a curved plate member 33. It has a pivotal or swinging movement when shaft 32 is partially rotated.

To the end of shaft 32 is attached a cam lever 34, as shown in Fig. 3, to the lower end of which is attached a spring 35, which in 90 turn is fastened to the frame of the machine so as to hold the member 34 in tension against a cam 36 mounted on the main driving shaft 2. While the fruit is being cored it is held in the pocket formed between the 95 hooked star ends of the turret plates or disks 20 by plate 33. A stationary cover plate 37 is fastened to the turret castings 25 forward of the flap or cover plate 33.

I provide means for slicing the pineapples, comprising long narrow knife blades 38, positioned between adjacent turret plates or disks 20 and penetrating the turret to a depth slightly greater than the depth of the pockets formed between the hooked 105 star portions of plates or disks 20, so as to

allow the blades 38 to slice through pineapples carried by turret 19 as it carries the pineapple forward, as illustrated in Fig. 4. Means adjustably supporting knives 38 are provided, such as shown in Fig. 4, consisting of small hook bolts 39 and adjusting nuts 47.

Pineapple coring tube 40, carried by crosshead 10, is also supported by castings 12. It is reciprocated by the crosshead to core the pineapples at intervals when the turret is stationary intervening between its intermittent movements. An inner sleeve guard 41 encircling coring tube 40 is mounted between casting 12 and turret casting 25 (Figs. 2 and 6). Coring tube 40 has a sharpened mouth 42. For the reception of the mouth 42 of coring tube 40 I provide a coring knife guide 43. This member has an annular groove 44 which encircles a central core 45, over which the mouth of the coring tube 40 projects as it completes its coring stroke, thus preventing dulling of the sharpened mouth 42 and pushing the cored portion of the pineapple farther into the coring tube, and ultimately discharging successive cores from the opposite end of the coring tube. An outer sleeve guard 48 protecting the outer end of coring tube 40, projects from the frame, as shown in Fig. 9.

Fig. 7 illustrates the clamping means 46 by which turret hub members 22 are held fast to turret shaft 18.

In operation, the pineapples, which have previously been suitably prepared (pared and trimmed), are fed into the turret by suitable means such as chute A and received in the pocket, as at B in Fig. 4, between successive hooked star portions of turret disks 20 or plates 20. The fruit is carried forward as the turret revolves step by step, regulated by the Geneva wheel 17, until it reaches the coring position, indicated by C. While the shaft 2 is making one revolution, the Geneva wheel 17 and the turret 19 are moved forward one step or pocket and then locked in a temporarily fixed position by locking hub 15 engaging with the curved surface of the Geneva wheel 17. The crank disk 8 is so timed with the main driving shaft 2 that the coring tube 40 is pushed through the fruit while the turret is locked or stationary, the fruit being held by plate 33.

After the coring operation the next step or movement of the turret 19 brings the pineapple in contact with knife blades 38 and partially slices the pineapple, as illustrated at D in Fig. 4. The following intermittent movement of the turret 19 completes the slicing of the pineapple as shown at E, and by its own weight the cored and sliced pineapple releases itself from the turret 19 into a discharge device or hopper F where it is deposited on a belt conveyer G and carried to the assorting tables.

In my machine the pineapples remain in a horizontal position throughout the coring and slicing operations.

I claim:

1. In a machine of the character described, a revoluble turret having a plurality of ribbed fruit-conveying disk members and means for retaining the aforesaid members in a fixed relation, a plurality of parallel fixed knife blades disposed between the aforesaid disk members exterior of the ribbed portion, means for adjustably mounting the aforesaid members, and means for coring the fruit while retained in the disk members in advance of the slicing operation. 70

2. In a machine of the character described, a reciprocating fruit coring tube, means operatively connected with a main shaft for operating same, a revoluble turret comprising a plurality of plates having hooked star ends and means for mounting same in adjustable relation, fruit-slicing knives disposed between spaced portions of the aforesaid plates, and means for intermittently revolving the aforesaid turret. 75

3. In a machine of the character described, a turret adapted to retain pineapples in a horizontal position comprising a plurality of hooked star-pointed plates spaced apart one from the other by offset ribs, bolts and hub members for fastening the plates together, a spacing sleeve, turret supporting members mounted on the main frame of the machine, and spaced diagonal braces to which a portion of the turret supporting members is secured. 90

4. In a machine of the class described, a turret adapted to retain pine-apples in a horizontal position comprising a plurality of hooked star-pointed plates spaced apart one from the other by offset ribs, means (including a spacing sleeve) for mounting the aforesaid plates in adjusted relations, diagonal braces by which the aforesaid members are supported, a knife holder mounted between the aforesaid braces, a corresponding upper knife holder, a plurality of fruit slicing knives disposed between spaced portions of the turret plates, and means adjustably securing the knives to the knife holders. 105

5. In a machine of the class described, a turret adapted to retain pine-apples in a horizontal position comprising a plurality of hooked star-pointed plates spaced apart one from the other by offset ribs, means for mounting the aforesaid plates in adjusted relation, a plurality of fruit slicing knives disposed between spaced portions of the turret plates, means for adjustably mounting same, a curved plate member disposed exterior of the turret to engage and hold fruit therein and means for swinging the said plate to an inoperative position intermittently. 115

6. In a machine of the class described, a 120

125

revoluble turret adapted to retain pineapples in a horizontal position, means for intermittently revolving same, a curved plate member for retaining fruit in a fixed position in a pocket of the turret, a rotatable shaft supporting the plate, a cam lever actuating same, a spring attached to the opposite end of the cam lever and to the frame of the machine, and a cam actuated by the main 10 driving shaft and positioned to engage with the aforesaid cam lever intermittently, for the purpose described.

7. In a machine of the class described, a revoluble turret adapted to retain pine- 15 apples in a horizontal position comprising a

plurality of hooked star-pointed plates spaced apart one from the other by offset ribs, knife blades positioned between adjacent turret plates and penetrating the turret to a depth slightly greater than the depth of 20 the pockets formed between the hooked star portions of the turret plates, knife holders, and hook bolts and adjusting nuts securing the knives to the aforesaid knife holders.

In testimony whereof, I hereunto affix my 25 signature in the presence of two witnesses.

FRED W. WOLF.
